UNITED STATES PATENT OFFICE.

JOHN ELLIE DAVIS, JR., OF WEST POINT, MISSISSIPPI.

CAR-COUPING.

SPECIFICATION forming part of Letters Patent No. 407,996, dated July 30, 1889.

Application filed April 25, 1889. Serial No. 308,509. (No model.)

To all whom it may concern:

Be it known that I, JOHN ELLIE DAVIS, Jr., a citizen of the United States, residing at West Point, in the county of Clay and State 5 of Mississippi, have invented certain new and useful Improvements in Car-Couplings; and I do hereby declare the following to be a full; clear, and exact description of the invention, such as will enable others skilled in the art 10 to which it appertains to make and use the same.

My invention relates, generally, to couplings for cars, and particularly to automatic couplings of that class in which a link is used 15 as the connection between the cars.

The object of the invention is to improve upon constructions of this kind, and the nature of these improvements will hereinafter be fully described in the specification and 20 pointed out in the claims, reference being had to the accompanying drawings, in which—

Figure 1 represents an end elevation of a car; Fig. 2, a section of a coupling, showing parts ready to receive the link; Fig. 3, a section 25 showing the link in place; Fig. 4, a top plan of the coupling and the buffer in section; Fig. 5, a detail showing one of the weights; Fig. 6, a detail showing the elbow-dog and locking-cam; Fig. 7, a detail; Fig. 8, a side 30 elevation of the buffer with rod removed, and Fig. 9 an elevation of my form of coupling shown on one side and the old form on the other side.

A represents the draw-head, having the 35 usual flaring mouth. In the bottom of the draw-head an opening a is formed for the elbow a' of a link-retaining dog A' , which is pivoted to the draw-head in any desired manner. The longer arm a^2 of the retaining-dog 40 normally rests in a recess a^3 , formed in the bottom of the draw-head, so that the upper face will be flush with the bottom of the draw-head and not interfere with the link when inserted in the draw-head. The short arm 45 a^4 , which extends vertically when arm a^2 is in recess a^3 , is connected with said arm a^2 by the elbow a' , rounded on its upper angle, as shown, so that the link when entering the draw-head will have a curved surface to act 50 upon to upset the dog and throw the long arm a^2 into the slot of the link to hold it in place. In the upper side of the draw-head is a slot

a^5 for the locking-cam A^2 , pivoted at the front end and projecting into the space formed by the walls of the draw-head. The cam A^2 is 55 provided with an inclined face a^6 , against which the link acts to raise the cam, so that the link can reach the arm a^4 of the dog A' to upset it. The rear part of the cam is curved and forms a bearing for the long arm a^2 of 60 the dog when the latter is upset to hold the link. The upper side of the locking-cam is provided with an eye a^7 or other device for lifting the cam when it is desired to release the link. On each side of the slot a^5 are formed 65 slots a^8 and a^9 for the pivoted weights A^8 and A^9 . These weights are pivoted at their front end by a rod a^{10} , which also passes through the locking-cam A^2 . The front part a^{12} of the under side of these weights is beveled, so that 70 the link in entering the draw-head will be guided toward the short arm of the dog. The under side a^{13} of the weight is parallel with the upper side, and when the link has passed thereunder holds the latter in a horizontal position and ready to enter the draw-head on 75 the car to be coupled. The rear ends a^{14} of the weights are rabbeted and enter a recess a^{15} formed in the rear of the draw-head, and the lower end is provided with a heel a^{16} , 80 which engages with the bottom of the draw-head recess. The link in entering the draw-head first lifts the weights and locking-cam, strikes the short arm of the dog, which is thereby upset in such manner as to throw the 85 long arm through the slot of the link, and in a vertical position back of the locking-cam, which falls in front of said arm and locks it in place, while the weights, which also resume their normal position, hold the link 90 horizontally. By lifting the locking-cam and pulling on the link the position of the dog is reversed and the link will be free of the locking mechanism. The cam is then returned to its place and the coupling is ready to receive and lock the link in place. 95

To unlock the coupling, several means may be employed. One is a bar B , extending across the end of the car and having hand-grasp b at each end for turning or rocking the bar, 100 which is provided at its center with a crank-arm b' , connected with the eye a^7 by a chain b^2 . By turning the rocking bar B the locking-cam is lifted and the link is free to upset the

dog to its normal position and be withdrawn from the draw-head. A second bar B' , extending from a point near the top of the car and connected by a chain b^3 to the crank-arm b' , can also be lifted to remove the locking-cam from contact with the dog. The bar B' is provided with a pin or projection b^4 , which can be raised through the slot in guide b^5 and turned to hold the bar B' in an elevated position, said bar in turn holding the cam, so that the link will be free to pull out. The advantage of this is found in using a flying switch. The bar B' is set as above described and the cars behind it are released in time to take the switch on the run.

The shank D of the draw-bar is provided with a flat coiled spring, which resists the pulling and pushing movement of the draw-head and prevents the jarring that usually occurs when such means are not provided.

In coupling cars that are provided with my device the weights hold the link in such position that the end to be inserted is guided to the exact place; but in that class of devices where the link is free to move or hangs loosely from a pin some means must be provided for guiding them into the draw-head. One means for overcoming this is shown in the drawings, and consists of the curved guide-plate E , which normally hangs from the draw-head, to which it is pivoted by arms E' E' on the bolt e , journaled in the draw-head. To raise the plate E into position any suitable device may be used. I prefer, however, to use a buffer I , having at its rear end a transverse passage I' . The end i of the passage is provided with an opening i' , and the opposite end is closed by a washer i^2 , held in the passage by flange or lugs i^3 . Between the end i and washer i^2 is interposed a coil-spring i^4 , which forces the

washer against the flange i^3 . The ends of arms E' are provided with a chain E^2 , passing over a pulley e^2 , secured to the car and connected to the end of a pull-rod I^2 , which passes through the passage I' to the side of the car. The rod I^2 is provided with a cross-head i^5 , which, when the rod is pulled, passes through a slot i^6 in the washer i^2 and is turned to engage with the groove i^7 in the face of the washer. When the link strikes the plate E , all jar is avoided, as the blow is more or less relieved by the arms E' drawing upon the chains and rod, which forces the washer against the spring in the lateral passage. When the plate E is not used, the washer can be released from the cross-head, and the weight of the plate will draw the rod I^2 to its normal position.

What I claim as new is—

1. In a car-coupling, the combination of an angular dog pivoted at the elbow to the bottom of the draw-head, a pivoted locking-cam projecting into the draw-head in front of the vertical arm of the dog, and the pivoted weights on each side of the locking-cam and having the inclined front ends to guide the link to the dog, substantially as described.

2. The combination of a draw-head, a guide-plate having arms and pivoted to the draw-head, a buffer having a passage provided with a spring and a slotted washer, a pull-rod having a cross-head and extending through said passage, and a chain passing over a pulley and connected with the guide-plate arms and the end of the pull-rod.

In testimony whereof I affix my signature in presence of two witnesses.

JOHN ELLIE DAVIS, JR.
